[57] CLAIM

The ornamental design for a merchandising indicator, as shown and described.

DESCRIPTION

FIG. 1 is a perspective view of a merchandising indicator showing my new design;

FIG. 2 is a right side elevation thereof, the opposite side being the same in appearance;

FIG. 3 is a rear elevation thereof; and

FIG. 4 is a top plan view thereof, the bottom being the same in appearance.

The broken line disclosure of the numerals in FIG. 1 is for illustrative purposes only and forms no part of the claimed design.
